REUBEN FREDERICK LADIN, OF NEW YORK, N. Y.

CONCRETE CONSTRUCTION.

1,180,931.

Specification of Letters Patent. Patented Apr. 25, 1916.

Application filed April 30, 1915. Serial No. 24,873.

To all whom it may concern:

Be it known that I, REUBEN FREDERICK LADIN, a subject of the King of Sweden, and a resident of the city of New York, borough of Manhattan, in the county and State of New York, have invented a new and Improved Concrete Construction, of which the following is a full, clear, and exact description.

10 This invention relates to artificial wall construction and has particular reference to concrete devices.

15 Among the objects of the invention is to provide improved facilities for erecting a wall of any suitable size, thickness or form and for any desired purpose such, for instance, as dams, abutments, building walls or the like, either vertical or battering, by the employment of means including a plurality of plates, panels or blocks designed to be arranged opposite each other in pairs and suitably connected in spaced relation and with the space filled with plastic material, said plates or blocks together with the plastic material coöperating and combining to 25 form the improved structure.

30 The foregoing and other objects of the invention will hereinafter be more fully described and claimed and illustrated in the drawings forming a part of this specification in which like characters of reference indicate corresponding parts in all the views, and in which

35 Figure 1 is a perspective view of a section of concrete wall indicating the nature of this invention and the manner of forming a wall thereby; Fig. 2 is an enlarged perspective view of one of the plates or shells, parts being broken away to disclose 40 the interior structure; Fig. 3 is a view of a corner piece made in accordance with this invention; and Fig. 4 is a modification of a reinforcement which may be employed.

45 The several parts of this device may be made of any suitable materials, and the relative sizes and proportions, as well as the general design of the mechanism, may be varied to a considerable extent without departing from the spirit of the invention 50 hereinafter more fully described and claimed.

55 Referring more particularly to the drawings I show at 10 one of the above referred to plates, the same comprising a vertical or substantially vertical portion 11 and a horizontal or substantially horizontal flange

portion 12 formed integral with the side 11 and at a definite angle thereto, the angle depending upon the nature of the wall to be constructed, whether vertical or battering. 60 In other words, the cross section of the plate 10 is substantially L-shaped and having the upper edge 13 parallel to the bottom surface 14.

65 In the construction of a wall with the employment of these plates or shells, the procedure is as indicated in Fig. 1 and comprises the placing of a horizontal row or layer along a suitable foundation (not shown), the plates 10 being arranged in 70 pairs, the faces of each pair being arranged opposite each other and with their base flanges 12 extending toward each other in the same horizontal plane, the space between the plates on the upright sides thereof being determined by the desired thickness of the wall. By the term "wall" as used herein I wish to be understood as comprehending any concrete structure or the like adapted to be erected for any purpose 80 through the operation of this invention. The lowermost row or layer of pairs of plates being placed in intended position, they will be crosstied or anchored by suitable means to maintain them spaced as designed by the architect or builder, and after being so braced or crosstied, the space between them will be filled with plastic material, such as soft concrete or the like, with suitable tamping. That is to say, the space 90 will be filled up level with the edges 13 of the opposing members of the pairs of plates.

85 In placing the individual plates or shells in position, those which come adjacent to each other, either end to end or edge to edge 95 are laid in courses of high grade cement indicated at 15. In other words, after one layer of the wall is completed, such layer comprising oppositely arranged rows of plates together with the filling of plastic 100 material, the next layer or course of plates will be superposed thereupon, the bottom surfaces 14, or the outer portions of such surfaces, being placed upon the upper edges 13 of the next lower course and connected 105 by the cement 15. The inwardly projecting flange portion 14, however, of each plate or shell will be supported upon the plastic material 16 previously introduced in the space beneath. Such plastic material constitutes 110 a binder and a direct support for said flange portion of the next upper course and ob-

viously stiffens and strengthens the structure. It will be understood that the plates or shells 10 become a permanent part of the wall structure and take the place of all temporary planking or the like which is so costly and troublesome in the making of a wall under usual conditions.

Each plate or shell 10 may be suitably reinforced by any sort or design of metal work either as bars or strips of woven material, the same being identified in the drawings by the character 17 and comprising a reticulated net work of wire or rods, depending upon the size and design of the plates. The reinforcing material preferably is coextensive with the length of the plate and also with both angularly related parts thereof. As additional reinforcing and bracing means I may employ diagonally arranged rods or braces 18 extending from the flange 12 to the upper portion of the side member 11 and spaced from the angle between the two parts. Such bracing rods may constitute a portion of the main reinforcement of the plate or may be attached thereto or otherwise locked in the structure of the plate. The portions of the bracing rods which are spaced from the angle of the plate constitute also interlocking means for coöperation between the plates and the filler 16, the plastic material being poured or tamped around such rods and within such spaces during the formation of the wall. I provide each of the plates with a plurality of attachment devices by connection with which I am able to anchor the several plates to one another either transversely or diagonally in vertical planes transverse to the general length of the wall. By way of illustration I show eyes 19 formed as stiff integral parts of the diagonal braces 18, said eyes projecting inwardly from the inner edge of the base flange 12 and from the upper portions of the side portion 11. As shown in Fig. 1, I may employ a cross connector or link 20 extending directly between the oppositely arranged eyes 19 of the pair of base flanges 12. Likewise a transverse strut or link 21 may be used to connect the eyes 19 of the upper portions of said opposite plates. At 22 I show diagonal ties or braces extending from the eyes 19 at the upper portions of the plates down to points adjacent the flanges 12 or their eyes 19, or, as shown in Fig. 1, these diagonal ties 22 may be connected to anchor members 23 embedded in the plastic material 16 between or below the base flanges

12. The application of the plastic material 16 as already described obviously takes place 60 after the anchoring and bracing has been done and such plastic material, because of its nature, readily adapts itself to the interstices or spaces between said links or other interlocking devices and the already hardened portions of the wall.

In Fig. 3 I show a corner piece for making a turn in the wall as in building a house or the like, the same comprising upright side members 11' and base flanges 12' related to 70 one another as already described in connection with the main wall plates and also having bracing and anchoring devices which may be of the same nature as described above. The corner may be furthermore reinforced by means of a diagonal link 24 extending from one of the eyes 19 to an anchor 25 embedded in the side member 11' in its formation.

Fig. 4 indicates a form of reticulated reinforcing means 17' in which an eye 19' is formed as an integral feature thereof.

In the practical operation of this method of forming walls I sometimes prefer to employ vertical plates of sheet metal or their 85 equivalent as indicated at 26 to protect the high grade cement between abutting ends of the plates 10 from the moist concrete 16 when the latter is being applied in a soft wet plastic condition. Said plates 26 obviously may be of any suitable sheet tin 90 or the like and add very little to the cost of the wall, and, after serving their purpose above set forth, may remain in place in the wall without objection. Obviously such 95 plates may consist of a sheet of building papers or other suitable material to temporarily protect the plate joint and cement from the wet concrete.

I claim:

In a building block of the nature set forth, the combination of base and side members rigidly connected in intersecting planes, embedded reinforcing means coextensive with the said base and side members and in the 105 form of a web, diagonal reinforcing elements extending between the base and side members and having their ends extended beneath the said reinforcing web and terminating at their extremities in attachment 110 eyes projecting inwardly from the said base and side members for the purpose described.

REUBEN FREDERICK LADIN.
